ATTORNEY

UNITED STATES PATENT OFFICE.

AMOS SHACKLETON HOLT, OF GLEN RIDDLE, PENNSYLVANIA.

CALENDAR.

Application filed February 18, 1924. Serial No. 693,699.

To all whom it may concern:

Be it known that I, AMOS SHACKLETON HOLT, a citizen of the United States, residing at Glen Riddle, in the county of Delaware and State of Pennsylvania, have invented new and useful Improvements in Calendars, of which the following is a specification.

This invention relates to calendars and 10 more particularly to a permanent calendar which is designed not only to permit quick and accurate ascertaining of the day and date, but which will, owing to the operation of the same, impress upon the mind of the 15 operator or owner, the day of the week and the month, and one which is constructed in such a manner as to be fascinating in a certain degree, to the operator.

Another object of this invention is to 20 provide a calendar as specified, which includes a board or body provided with a plurality of perforations one for each day in the year and arranged in series simulating the days of the month and to provide 25 colored pegs adapted for insertion into the perforations, to indicate the days and dates and further, to provide in close proximity to the date indicating perforations for indicating the various days of the week, with which 30 perforations a peg of different color from the date indicating peg is used, and also to provide a plurality of pegs of special or particular colors which may be used as reminders as desired.

Another object of the invention is to provide a calendar structure to record with 35 movable pegs and printed perforated board, the day of the week, the day of the month, and the month of the year, and the year of 40 the "Gregorian calendar."

Other objects of the invention will appear in the following detail description, and in the accompanying drawings wherein:

Figure 1 is a face view of the improved 45 calendar.

Figure 2 is a cross section through the calendar.

Referring more particularly to the drawings, the improved calendar comprises a 50 body board 1 which may be constructed of any suitable material and in any suitable manner similar to the manner of constructing what is commercially known as "punchboards." On the face of the body 1 is print-

55 ed in suitable spaces preferably adjacent each vertical edge, the consecutive numbers

from 1 to 31 to represent the date or day of the month, and the space of the face of the body 1 between the two series of numbers is divided into twelve longitudinally extending columns 3 which are indicated at both upper and lower ends of the columns with suitable indices representing the months of the year. The various columns 3 are divided by transversely extending lines into 60 31 spaces corresponding with the numbers in the side rows 2 and these spaces are perforated. Each column is perforated only with a number of openings corresponding to the number of days in the respective 65 months of the year, for example, the column indicating the month of January, has a perforation in each of the spaces or has 31 perforations therein whereas the column for the month of April, has but 30 perforations. 70 It will be noted that the column for the month of February has 29 perforations, so as to adapt the calendar for both regular and leap years. 75

Above the columns 3, the board 1 is provided with 6 perforations, 4 arranged in a straight line transversely of the body and these 6 perforations have suitable indices associated therewith to indicate the working days of the week. A seventh perforation 80 5 is positioned above the row of perforations 4 and it has indices associated therewith to indicate Sunday.

At the bottom of the body 1 beneath the columns 3 are provided any desired number 85 of perforations 6 preferably arranged in a straight row and the word "Reminder" is printed in close proximity to these last named perforations 6.

A peg 7 which is preferably of a distinctive color such as red, is provided for co-operation with the various perforations in the columns 2 and a second peg 8 of a different distinctive color, as for example, blue, is provided for co-operation with the perforations 4 and 5, while pegs 9 of distinctive colors, different from the colors of the pegs 7 and 8, are provided, and which normally rest in the perforations 6, at the bottom of the body 1. These latter pegs 9 100 are adapted to be placed in any one of the perforations in the columns 2 to serve as a reminder to the owner of the calendar for special things to be remembered on special 105 days. 110

The portion of the face of the body 1 above the perforations 4 and 5 may serve

as an advertising space, or for receiving any suitable type of printing.

In operating the calendar, for instance, the present day is Friday, January 11th, 5 and the red peg 7 is placed in the perforations in the January column 2, in the transverse row aligning with the numbers 11 in the series of numbers along the edges of the face of the board and the blue peg 8 is 10 placed in the perforations 4 indicating Friday, and upon the following day, the blue peg 8 is moved into the perforations 4 indicating Saturday, and the red peg 7 is moved forward one perforation and into 15 alignment with the #12 thereby indicating that the day is Saturday, January 12th.

The improved calendar illustrated in the accompanying drawings, and just described, is essentially an individual calendar, and by 20 moving the pegs to record the day and date from day to day, the same seemingly arrests the flight of time and impresses the mind of the operator with the day and date enabling him to more readily remember this without 25 particular reference to the calendar. The calendar is also particularly adapted for use by the blind, in that they could readily tell the date by the sense of touch.

It is to be understood that the various pegs 30 may be made of any suitable material, any suitable style or color without departing from the spirit of this invention, and if it is so desired, when the calendar is used in a year other than a leap year, one of the reminder pegs 9 may be inserted in the perforations 29 in the February column 2, to obliterate these perforations.

It is, of course, to be understood, that the invention may be constructed in various 40 other manners and the parts associated in different relations, and therefore, I do not desire to be limited in any manner, except as set forth in the claims hereunto appended.

What I claim is:

45 1. As a new article of manufacture, a calendar comprising a body provided with a plurality of perforations one for each day of the year, and with a second plurality of perforations one for each day of the week, 50 said body having printed thereon in proximity to the various perforations, suitable indicating indices and pegs for insertion in said perforation and co-operating with said indicia to permit the user to readily determine the day of the week and date of the 55 month.

2. As a new article of manufacture, a calendar comprising a body having printed on the face thereof, adjacent its opposite edges, rows of numbers in sequence to indicate the days of the month, said body between said rows being divided into columns to represent the months of the year, and each of said columns being cross divided and perforated to provide a perforation for each day of the month, and a peg for insertion in said perforation. 60

3. As a new article of manufacture, a calendar comprising a body having printed on the face thereof adjacent its opposite edges, rows of numbers in sequence to indicate the days of the month, said body between said rows being divided into columns to represent the months of the year, and each of said columns being cross-divided and 70 perforated to provide a perforation for each day of the month, and a peg for insertion in said perforation, said body provided with a plurality of perforations positioned above said columns, said last named perforations being provided to indicate the days of the week and a peg of different appearance than said first named peg for co-operation with the last mentioned series of perforations. 75

4. As a new article of manufacture, a calendar comprising a body having printed on the face thereof adjacent its opposite edges, rows of numbers in sequence to indicate the days of the month, said body between 90 said rows being divided into columns to represent the months of the year, and each of said columns being cross-divided and perforated to provide a perforation for each day of the month, and a peg for insertion in said perforation, said body provided with a plurality of perforations positioned above said columns, said last named perforations being provided to indicate the days of the week and a peg of different appearance than said first named peg for co-operation with the last mentioned series of perforations, said body provided with a series of perforations below said first mentioned perforations, said last named lower perforations being provided for retaining reminder pegs, and a plurality of reminder pegs of different appearance from the day and date indicating pegs. 100

In testimony whereof I affix my signature.

AMOS SHACKLETON HOLT.
